ULTRA VIOLET LAMP

John Wesley Marden and Madison G. Nicholson,
Jr., East Orange, N. J., assignor, by mesne assignments, to Westinghouse Electric and Manufacturing Company, East Pittsburgh, Pa., a corporation of Pennsylvania

Application November 19, 1931, Serial No. 576,022

26 Claims. (Cl. 176—122)

This invention relates to electric lamps and is more particularly directed to lamps of this character adapted to be employed for the production of rays, and especially a spectrum relatively rich in ultra violet rays. Gaseous conduction lamps of the negative glow type yield ultra violet rays and are generally termed glow lamps and it is with this particular class of lamps that the invention is specifically concerned and will hereinafter be particularly described.

These lamps generally comprise an exhausted bulbous or cylindrical gas tight enclosing envelope having a small proportion of mercury therein and if desired also a small quantity of a monatomic gas such as helium, neon, argon or the like. The envelope commonly has a re-entrant stem with a press in which are sealed a pair of lead-in wires and supporting wires, the latter extending into said envelope and having upper free ends in spaced relation therein.

Electrically secured to said free ends and supported thereby is a pair of spaced parallel heater elements extending in a direction approximately parallel to the longitudinal axis of the bulb and being located in or closely adjacent the virtual longitudinal center plane of the envelope. Each of said heater elements is surrounded by a thermionically active cylindrical cathode whose inner surface is spaced from the heater element.

In the course of our experimentations with lamps of this character, we have found that the quantity of ultra violet radiations produced thereby is generally dependent on the magnitude of the current, and that the life and efficiency of these lamps is dependent on the magnitude of the current and its relation to the sizes of the electrodes, internal supporting leads and the heater elements. That is to say, for example, a glow lamp characterized by 40-60 mils nickel internal support leads, 75 turns of 125 turns per inch of a 21 milligram wire wound on a 21 mil mandrel as heater filaments and thermionically active electrodes 14.5 mm. long and 122 mils outside diameter may be efficiently operated at about 20 volts and 1.25 amperes for a comparatively long period of time.

If, however, a lamp of the same construction and size were operated at about the same voltage and about 2.5 amperes, its life would be considerably decreased. These consequences are due mainly to overheating of the internal structure of the lamp and loss of electron emission because of the excessive bombardment of this internal structure by the electrons and positive ions.

In order that we may be enabled to produce large quantities of ultra violet radiations by employing a single lamp at a comparatively high amperes, we may provide said lamp with an internal structure characterized by thermionically

active electrodes, support leads and filaments of comparatively large sizes so that the life of the lamp shall be of a practical value. Such a lamp because of the large envelope necessary to accommodate its large internal structure, is not amenable to the degree of compactness and to other advantages characterizing the present invention.

One other disadvantage incident to the employment of large electrodes is that it is difficult to maintain the proper amount of electron emission therefrom. It is often found that when electrodes of a size sufficiently large to withstand bombardment are employed with a coating of the best available thermionically active material, that the number of electrons emitted therefrom is greater than that desired for a given voltage drop between the electrodes.

Other difficulties include especially that of excessive bombardment which may cause sputtering of the support leads and/or vaporization of the thermionically active material on the electrodes. The latter is generally incidental to the operation of a compact 1.25 ampere lamp, heretofore described, when said lamp is operated at 2.5 amperes. To obviate these disadvantages we have provided the present invention. Besides having these important properties the diffusibility of the negative glow produced in a lamp embodying our invention is materially enhanced.

The invention in its specific aspect briefly stated comprises a gas-tight exhausted envelope containing therein a small proportion of mercury and, if desired, also a small proportion of a monatomic gas such as helium, neon or argon. Within said envelope are mounted heating coils, each surrounded by and spaced from a thermionically active electrode having shielding means associated therewith.

An object of the invention is to provide a lamp of the gaseous conduction negative glow type, which is simple, compact, and adapted to operate efficiently at comparatively high amperages for a relatively long period of time.

Another object of the invention is to provide a relatively compact lamp adapted to produce a negative glow rich in ultra violet radiations and characterized by relatively high diffusibility.

A further object of the invention is to provide a lamp of the negative glow gaseous conduction type whose efficiency is relatively high and which is adapted to operate for a comparatively long period of time under predetermined conditions.

Other objects and advantages of the invention will be apparent from the following description and drawing wherein,

Figure 1 represents a horizontal sectional view, with some parts shown in plan, of an embodiment of our invention;

Figure 2 represents a developed elevational

view of the envelope-contained parts of the embodiment shown in Figure 1, with the envelope omitted, some of the parts being shown in section and others diagrammatically;

Figure 3 represents a side elevation, with some of the parts in section, of another embodiment of our invention;

Figure 4 is a section taken on line IV—IV of Figure 3;

Figure 5 represents the vital internal structure with the electrical connections of the embodiment illustrated in Figure 3;

Figure 6 is a cross sectional view, similar to Figure 4, of a modification of the internal structure shown in Figure 3;

Figure 7 is a view, similar to Fig. 3, of still another embodiment of our invention.

In order that a compact glow lamp heretofore employed, as for example, a 1.25 ampere glow lamp may be operated on a higher current, as for example 2.5 amperes, without any decrease in its efficiency or minimizing of its life, there is provided the structure shown in Figure 1 as an illustrative embodiment of our invention. As will be hereinafter apparent, these results are possible, without increasing the size of any one electrode and without increasing the size of the enclosing envelope, because we utilize the space on either side of the virtual plane embodying the two parallel electrodes of the 1.25 ampere lamp.

As shown in Figures 1 and 2, an embodiment of our invention comprises a gas-tight exhausted envelope consisting of a bulb 10 and a reentrant stem 11 having a press 12. The bulb 10 may be of any suitable material, such as quartz or the like, which is permeable to the ultra violet radiations produced therein. The stem 11 is provided with an upstanding wire pedestal 13 and with the customary exhaust tube (not shown) and in the envelope is disposed a small quantity of mercury vapor for the efficient operation of the lamp. If desired, there may be also contained therein a small proportion of a monoatomic gas such as helium, neon, argon, or the like.

Sealed into the press 12 are a plurality of lead-in wires 15 and 16 and supporting wires 17 and 18 which are electrically connected to the respective lead-in wires 15 and 16. These support wires 17 and 18 may be composed of nickel and extend upwardly and outwardly from the press 12.

Adjacent the free ends of the respective support wires 17 and 18 are electrically secured, as by means of welding, rigid guides or support leads 19 and 20 on the upper ends of which are weldedly secured coiled heater filaments 21 and 22 respectively. These filaments 21 and 22 are of materially lesser cross sectional area than the respective guides or supports 19 and 20 and are respectively weldedly secured to a pair of upper guides or support leads 23 and 24. Telescoping with the filaments 21 and 22 are electrodes 25 and 26 respectively, each consisting of a cylindrical metallic base such as nickel, having an outer coating of a thermionically active material, such as an alkali or alkaline earth, as for example barium oxide.

The lower ends of these electrodes 25 and 26 have respectively welded thereto conducting wires 25' and 26' which are also welded to the support wires 17 and 18 respectively. These electrodes are spaced about 180 degrees apart and are approximately located in an axial plane of the bulb 10.

With the type of glow lamp heretofore em-

ployed there is a connecting wire secured to the ends of the upper supports or leads 23 and 24 in order to complete the circuit. In our invention, however, we depart from the prior art by utilizing the space on each side of the virtual longitudinal plane of these electrodes by providing an electrode structure in each of said heretofore unused spaces.

As shown in Figures 1 and 2, our invention may be carried out by welding a cross arm 27 of nickel wire to the lower portion of the vertical support 13. Upstanding rigid supports or guide leads 28 and 29 are secured, as by electric welding, to the respective ends of the cross arm 27. At the upper ends of the respective leads 28 and 29 are weldedly secured coiled filaments or heater elements 30 and 31, similar in all respects to the filaments 21 and 22, and at the upper ends of these filaments 30 and 31 are weldedly secured upper ridge guides or support leads 32 and 33. Telescoping with the filaments 30 and 31, mounted in the same general manner and of the same general composition as electrodes 25 and 26, are electrodes 34 and 35.

The filaments 21, 30, 31 and 22 are connected in series by means of the support 27 and nickel wires 36 and 37, the latter being welded to the pairs of upper rigid guides or support leads 23, 32 and 24, 33 respectively. The electrodes 25 and 35 are connected in parallel, and therefore 30 are at the same potential in operation, by means of connector 38, and electrodes 26 and 34 are connected in parallel, and are at the same potential in operation, by means of connector 39.

In order that our novel lamp shall be amenable to efficient operation and comparatively long life, the electrodes 25, 26, 34 and 35 are so arranged within the bulb 10 that they all are substantially parallel to and approximately equi-spaced from the longitudinal axis of the lamp, and disposed on approximately the same virtual circumference about ninety degrees apart.

We have found that with a lamp of this general construction larger quantities of ultra violet rays may be produced because it permits the employment of higher amperage without any material decrease in life or efficiency which was not possible with the same size lamps heretofore employed.

Besides this our novel lamp has the further salient advantage that the amount of ultra violet radiations produced therewith at a certain amperage value is greater than that produced in any other single or plurality of two electrode lamps operating at the same amperage. That is to say, the quantity of ultra violet radiations produced by an ordinary two electrode 2.5 ampere, large size glow lamp or by two relatively compact small size 1.25 ampere glow lamps is less than that produced by our novel 4 electrode glow lamp whose size may be that of the 1.25 ampere lamp and whose electrodes and filaments are of the same size as those of the 1.25 ampere lamp. Further advantages of this particular structure are that the amperage may be materially increased above 2.5 without impairing the efficiency or decreasing the life of the lamp and, moreover, the diffusibility of the ultra violet rays is considerably enhanced. Although we have compared our novel glow lamp of a size corresponding to that of a 1.25 ampere glow lamp, we do not mean to be limited thereby but have merely used this particular size as an illustration for the sake of clearness of comparison.

In order that we may further enhance the diffusibility of the radiations produced in our

novel lamp heretofore described, we provide its internal structure with one or more shields or grids which also serves to increase the efficiency and life of the device and permits the employment of still higher amperages without decreasing the normal life of the lamp.

For these purposes we provide one or preferably two shields or grids 40 and 41 as shown in Figures 1 and 2. Each of these shields or grids may be in the form of a nickel wire 20 mesh screen or a perforated plate of nickel or the like, characterized by an outwardly flared V shape and of a width materially greater than the length of the electrodes. The shield or grid 40 is mounted between the electrodes 34 and 25 and the shield or grid 41 is mounted between the electrodes 35 and 26 with the apices of the screens or grids opposite each other and the flared portions thereof being in approximately parallel relation with and spaced from each other. The grid 40 is maintained at the same potential as the electrodes 25 and 35 and the grid 41 is maintained at the same potential as the electrodes 26 and 34. For this purpose we provide rigid nickel supporting wires 42 electrically secured, as by welding, to one arm of the grid 40 and to the lead 17, and a rigid supporting wire 43 electrically secured as by welding to one arm of the grid 41 and the lead 18.

The structure is braced at its upper ends by means of an elongated glass bead 44 firmly sealed to the pedestal 13, and carrying a plurality of wires 45 and 46 which are welded to the cross arms 36 and 37 respectively.

The cross arms 36 and 37 carry a plurality of glass beads to which are secured wires 47 and 48, welded to the arms of the grids 40 and 41 respectively. These wires are mere supporting means and the glass beads serve as bracing means and insulating media between them and the cross arms.

Instead of using a four cathode structure as shown in Figures 1 and 2, one other aspect of our invention is the embodiment shown in Figures 3, 4 and 5. As illustrated, we may employ but two electrodes in the lamp which comprises an exhausted envelope 58, of the type heretofore described, and contains a small proportion of mercury and, if desired, a small quantity of a monatomic gas such as neon, argon or the like. Extending upwardly and outwardly from the press and sealed thereto are a plurality of nickel supporting wires 51 and 52. These wires are electrically secured to lead-in wires 53 and 54 respectively, and have rigid guide or support wires 56 and 57 electrically secured thereto adjacent the free ends thereof as by means of welding. To the upper end of these guides or supports 56 and 57 are electrically secured, as by means of welding, coiled heater filaments 58 and 59, to the upper ends of which are electrically secured upper rigid guides or supports 60 and 61, which are in turn welded to a common cross wire 62.

The cathode assembly illustrated is of the type heretofore described and consists of sleeves 63 and 64 respectively surrounding and spaced from the filaments 58 and 59. Each of these electrodes comprises a cylindrical sleeve consisting of nickel base having a coating of a thermionically active material thereon and is secured to its respective guide or support in the manner heretofore described.

Adjacent the support leads 60 and 61 is an elongated glass bead 65 having metallic spurs 75

66 and 67 integrally united therewith and secured to the cross arm 62.

In order that a construction of this character may be operated at relatively high amperages to produce relatively large quantities of highly diffused ultra violet radiations without the necessity of materially increasing the size of the lamp, we provide according to our invention a shield or grid, or preferably a plurality of shields or grids 68 and 69, hereinafter described, surrounding the electrodes 63 and 64 and spaced from the outer surface thereof. Each of these shields or grids 68 and 69 may be in the form of a 20 mesh nickel wire screen whose diameter is materially greater than that of the electrodes 63 and 64, and are kept at the same potential as the respective electrodes by means of electrical connector 70 welded to the lower portion of the grid 68 and to the support lead 51, and electrical connector 71 welded to the lower portion of the grid 69 and to the support lead 52. The shields or grids are braced at their upper ends by means of U wires 72 and 73 welded to the respective pairs of elements 63, 68 and 64, 69 and by means of wires 74 and 75 integral with the bead 65 and welded to the respective shields or grids 68 and 69.

In order to further improve this lamp, we provide a longitudinally extending plate or mesh nickel shield 76 located between and equidistantly spaced from the electrodes and shielding one electrode from the other.

Unlike the grids 68 and 69 the shield 76 is not connected to either of the leads 51 or 52, but is carried by the insulator 65 and another insulator 77 secured to the supports 51 and 52. This shield is of a width greater than the diameter of the grids 68 and 69 and its longitudinal edges are located beyond the periphery of each of these grids.

As an alternative shield or grid structure, we may employ a plurality of parallel nickel rods 80 circumferentially spaced around each electrode as shown in Figure 6.

Still another embodiment of our invention is shown in Figure 7. As illustrated there is provided a common two electrode glow lamp of the type heretofore described, with a shield or grid 96. This shield 96 may be of about a 100 mesh nickel screen carried by a supporting wire 97 which may have one end sealed to the press of the envelope and its other end welded to the cross arm connecting the two filaments. The shield per se may be of a width which is about four to eight times the diameter of the electrodes and may be composed of nickel or the like in the form of a plate, mesh or spaced rod structure. Like the shield 76 of the embodiment shown in Figure 3, this shield 96 is in a broadside position between the electrodes and serves to spread out the discharge and reduces the quantity of ions going directly from one electrode to another. These considerations are of importance in the operation of lamps of this character because of the diffusibility of the radiation produced, the efficiency and the life of the lamp which are increased by means of the construction heretofore described.

Although we have shown and described several specific embodiments of our invention, we do not desire to be limited thereto, as various other modifications of the same may be made without departing from the spirit and scope of the invention as defined by the appended claims.

We claim:

1. A negative glow lamp of the gaseous conduction type comprising an enclosing envelope having four electrodes therein, two of said electrodes being in parallel electrical relationship with each other and the other two of said electrodes also being in parallel electrical relationship with each other, said four electrodes spaced from each other and approximately located on a common virtual circumference. 5
2. A negative glow lamp of the gaseous conduction type comprising an enclosing envelope having four electrodes therein, two of said electrodes being in parallel electrical relationship with each other and the other two of said electrodes also being in parallel electrical relationship with each other, said electrodes spaced about 90° apart and located adjacent a common virtual circumference. 10
3. A negative glow lamp of the gaseous conduction type comprising an enclosing envelope having four electrodes therein, two of said electrodes being in parallel electrical relationship with each other and the other two of said electrodes also being in parallel electrical relationship with each other, each of said electrodes being generally parallel to the longitudinal axis of the envelope and located adjacent a common virtual circumference, each of said electrodes being spaced about 90° apart. 15
4. A negative glow lamp of the gaseous conduction type comprising an enclosing envelope, a plurality of closely spaced thermionically active electrodes therein, a grid located between said electrodes and disposed closer to one than the other, and means directly connecting said grid to the closer electrode so that they always operate at the same potential. 20
5. A negative glow lamp of the gaseous conduction type comprising an enclosing envelope, a plurality of thermionically active electrodes therein, a woven wire grid located between said electrodes, said grid being directly connected, and closer, to one of said electrodes than the other, so that it is always at the same operating potential as said connected electrode. 25
6. A negative glow lamp of the gaseous conduction type comprising an enclosing envelope, a plurality of closely spaced electrodes therein and a plurality of grids located adjacent to said electrodes, one of said grids being directly connected to one of said electrodes so as to always have the same operating potential, and the other grid being directly connected to the other electrode so as to always have the same operating potential. 30
7. A negative glow lamp of the gaseous conduction type comprising an enclosing envelope, a plurality of closely spaced thermionically active electrodes therein and a grid surrounding and spaced from one of said electrodes, said grid being directly connected to said electrode so as to always have the same operating potential. 35
8. A negative glow lamp of the gaseous conduction type comprising an enclosing envelope, a plurality of closely spaced electrodes therein, a grid surrounding and spaced from each of said electrodes, each of said grids being directly connected to the electrode surrounded thereby so as to always have the same operating potential. 40
9. A negative glow lamp of the gaseous conduction type comprising an enclosing envelope having four electrodes therein, two of said electrodes being in parallel electrical relationship with each other and the other two of said electrodes also being in parallel electrical relationship with each other and a grid located between two of said electrodes. 45
10. A negative glow lamp of the gaseous conduction type comprising an enclosing envelope having four electrodes therein, two of said electrodes being in parallel electrical relationship with each other and the other two of said electrodes also being in parallel electrical relationship with each other and a grid located between two of said electrodes, said grid being in parallel electrical relationship with one of said electrodes. 50
11. A negative glow lamp of the gaseous conduction type comprising an enclosing envelope having four electrodes therein, two of said electrodes being in parallel electrical relationship with each other and the other two of said electrodes also being in parallel electrical relationship with each other, said four electrodes spaced from each other and approximately located on a common virtual circumference and a grid located between two of said electrodes. 55
12. A negative glow lamp of the gaseous conduction type comprising an enclosing envelope having four electrodes therein, two of said electrodes being in parallel electrical relationship with each other and the other two of said electrodes also being in parallel electrical relationship with each other, a plurality of grids located between said electrodes, one of said grids being in parallel electrical relationship with one of said electrodes and the other of said grids being in parallel relationship with another one of said electrodes. 60
13. A negative glow lamp of the gaseous conduction type comprising an enclosing envelope having four electrodes therein, two of said electrodes being in parallel electrical relationship with each other and the other two of said electrodes also being in parallel electrical relationship with each other, each of said electrodes including a thermionically active material and a heater element for rendering said material electron emissive, all of said heater elements being in electrical series relationship with each other. 65
14. An ultra violet lamp comprising an enclosing envelope, an ionizable medium therein, said envelope having a press, a plurality of electrodes supported by said press each of said electrodes including a heating element and a thermionically active material, the heating elements of said electrodes being in electrical series relationship and a grid located in the space between said electrodes and directly connected to the active material of one electrode so as to always operate at the potential thereof. 70
15. An ultra violet lamp comprising an enclosing envelope, an ionizable medium therein, a plurality of spaced thermionically active electrodes, a grid located in the space between said electrodes, said envelope having a press, said electrodes being supported by said press, each of said electrodes including a heater element and a hollow body having a thermionically active surface, said heater element being located in said hollow body for heating the same, said heater elements being connected in electrical series relationship, said grid being directly connected to one hollow body so as to always operate at the potential thereof. 75
16. An ultra violet lamp comprising an envelope, an ionizable medium therein, a plurality of thermionic electrodes and a grid also located therein, said electrodes being spaced from each

other, said grid being located in the space between said electrodes, each of said electrodes including a hollow body having a thermionically active surface and a heater element, said heater elements being connected in electrical series relationship, said grid being directly connected to one of said hollow bodies so as to always operate at the potential thereof.

17. An ultra violet lamp comprising an enclosing envelope, an ionizable medium, a plurality of electrodes and a grid located therein, said electrodes being spaced from each other and supported by a press, each of said electrodes including a heater element and a thermionically active material, a grid located in the space between said electrodes said grid being directly connected to the thermionically active material on one of said electrodes so as to always operate at the potential thereof.

18. An ultra violet lamp comprising an envelope, an ionizable medium, four thermionically active spaced electrodes and a grid located therein, each of said electrodes including a heater element and a thermionically active material, two of said electrodes being in electrical parallel relationship, said heater elements being in electrical series relationship, said grid being directly connected to one of said electrodes so as to always operate at the potential thereof.

19. An ultra-violet lamp comprising an envelope, an ionizable medium therein, a plurality of thermionic electrodes and a grid also located therein, said electrodes being spaced from each other and supported by a press, said grid being located in the space between said electrodes, each of said electrodes including a hollow body having a thermionically active surface and a heater element, said heater elements being connected in electrical series relationship, said grid also being supported by said press and directly connected to one of said hollow bodies so as to always operate at the potential thereof.

20. An ultra-violet lamp comprising an enclosing envelope, an ionizable medium, a plurality of electrodes and a grid located therein, said electrodes being spaced from each other and supported by a press, each of said electrodes including a heater element and a thermionically active material, a grid located in the space between said electrodes said grid being directly connected to the thermionically active material of one of said electrodes so as to always operate at the potential thereof.

21. A gaseous conduction lamp comprising an enclosing envelope, an ionizable medium therein, said envelope having a press, a plurality of electrodes supported by said press each of said electrodes including a heating element and a thermionically active material, the heating elements of said electrodes being in electrical series relationship, and a grid located in the space between said electrodes and directly connected to the thermionically active material of one of said electrodes so as to always operate at the potential thereof.

22. A gaseous conduction lamp comprising an envelope, an ionizable medium therein, a plurality of thermionic electrodes and a grid also located therein, said electrodes being spaced from each other and supported by a press, said grid being located in the space between said electrodes, each of said electrodes including a hollow body having a thermionically active surface and a heater element, said heater elements being connected in electrical series relationship, said

grid also being supported by said press and directly connected to one of said hollow bodies so as to always operate at the potential thereof.

23. A gaseous conduction lamp comprising an enclosing envelope, an ionizable medium therein, said envelope having a press, a plurality of electrodes supported by said press each of said electrodes including a heating element and a thermionically active material, the heating elements of said electrodes being in electrical series relationship, and a plurality of apertured electrically conducting cylindrical grid elements completely surrounding said electrodes respectively and each directly connected to the thermionically active material of the surrounded electrode so as to always operate at the potential thereof.

24. A gaseous conduction lamp comprising an envelope, an ionizable medium therein, a plurality of thermionic electrodes and a grid also located therein, said grid being formed as an apertured electrically conducting cylindrical element and completely surrounding at least one of said electrodes, said electrodes being spaced from each other and supported by a press, said grid being located in the space between said electrodes, each of said electrodes including a hollow body having a thermionically active surface and a heater element, said heater elements being connected in electrical series relationship, said grid also being supported by said press and directly connected to one of said thermionically active surfaces so as to always operate at the potential thereof.

25. A discharge lamp comprising a vitreous envelope containing gas at a relatively low pressure admixed with mercury vapor, a plurality of electrodes in said envelope, each electrode comprising a hollow tubular member having a surface adapted to emit electrons when heated, a lead from each tubular member directly to the exterior of the envelope whereby the potential of the energizing power is applied between said tubular members when the lamp is operated, means connected in series across said leads and comprising incandescent filaments disposed interiorly of said tubular members for heating them to electron-emitting temperature, and a grid associated with one of said tubular members and directly connected thereto so as to operate at the potential thereof and protect its electron-emitting surface from bombardment during operation of said lamp.

26. A discharge lamp comprising a vitreous envelope, a plurality of electrodes therein, each electrode comprising a hollow tubular member having a surface adapted to emit electrons when heated, a lead from each tubular member directly to the exterior of the envelope whereby the potential of the energizing power is applied between said tubular members when the lamp is operated, means connected in series across said leads and comprising incandescent filaments disposed interiorly of said tubular members for heating them to electron-emitting temperatures, a grid associated with each of said tubular members to protect its electron-emitting surface from bombardment during operation of the lamp, and a shield disposed broadside between said grids to spread out the discharge and reduce the quantity of ions going directly from one electrode to another.
